CLAIM

The ornamental design for a net for cleaning swimming pools, as shown and described.

DESCRIPTION

FIG. 1 is a perspective view of a net for cleaning swimming pools showing our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front end elevational view thereof; and,

FIG. 7 is a rear end elevational view thereof.

The crosshatched pattern along the netted portion is partially shown for ease of illustration only and is understood to continue throughout the areas indicated.
